UNITED STATES PATENT OFFICE.

RHEUBEN M. CLARK, OF JOPLIN, MISSOURI.

PUMP.

Application filed June 4, 1927. Serial No. 196,565.

This invention relates to pumps and more particularly to a pump especially designed and adapted for use in irrigation.

An important object of the present invention is to provide an efficient pump of the impeller type which is adapted to be employed without the use of baffles or similar devices to prevent the generation of centrifugal force.

10 A further object is to provide a pump structure including a casing having an inlet and an outlet, and to provide oppositely pitched impellers mounted upon a common shaft and adapted to pump liquids from the inlet of the casing to the outlet.

15 A further object is to improve the pumping action by employing impellers of the spiral type employing a pair of spiral blades by which it has been found that the centrifugal motion usually imparted to the liquid is minimized.

20 A further object is to provide means for increasing the pumping action by adding to the impellers without discarding the pump casing.

25 A further object is to provide a pump of the character just referred to wherein the casing may be lengthened to accommodate additional impeller sections when it is desired to increase the pumping pressure.

30 Other objects and advantages of the invention will become apparent during the course of the following description.

In the drawings I have shown several embodiments of the invention. In this showing:—

Figure 1 is a central vertical sectional view through one form of pump,

Figure 2 is a section on line 2—2 of Figure 1,

Figure 3 is a similar view on line 3—3 of Figure 1,

Figure 4 is a side elevation of a modified form of pump, parts being broken away,

Figure 5 is a side elevation of the pump shaft adapted to be employed with the pump illustrated in Figure 1,

Figure 6 is a detail view of a pair of impeller sections,

Figure 7 is a side elevation of a pump

shaft adapted to be employed in connection with the pump illustrated in Figure 4, and,

Figure 8 is a detail perspective of one of the lengthening sleeves.

Referring to the drawings the numeral 55 10 designates a pump casing which has an elongated preferably horizontal upper portion 11 provided in its center with an outlet opening 12. An outlet pipe 13 may be threaded in a flange 14 secured to the casing 60 by bolts or the like 15. The elongated portion of the pump casing is provided with a central cylindrical portion 16, as clearly shown in Figures 1 and 2. The casing is further provided with a depending portion 65 17 having a central inlet opening 18. The lower end of the extension 17 is flanged as at 19 and an attaching flange 20 may be bolted thereto as at 21. An inlet pipe 22 is threaded or otherwise secured to the flange 70 20. The upper portions of the lower extension 17 are provided with passages 23 through which water or other liquid is adapted to be supplied to the interior of the cylinder 16 in a manner to be described.

75 Each end of the casing is provided with extensions 24 forming continuations thereof and a head 25 is arranged against the outer end of each extension 24. The heads and extensions may be secured to the casing by bolts 26 as shown in Figure 1. Each end portion of the casing is provided with an annular recess 27 in which is seated the inner end of an extension sleeve 28, each sleeve forming an extension of the cylindrical portion 16, as will be apparent. A portion of the outer end of each extension 28 contacts with the inner end of one of the extensions 24 whereby it is maintained in position. Each of the heads 25 is provided with an inner axial extension 29 in which is arranged a babbitt or similar bearing 30.

80 A pump shaft indicated as a whole by the numeral 31 is mounted to rotate in the bearings. As shown in Figure 5, the pump shaft 95 is provided with an enlarged central portion 32 at each side of which there is provided a slightly reduced threaded portion 33 of substantial length. One end of the shaft is further provided with a relatively short cy- 100

cylindrical extension 34 which is slightly smaller than the adjacent threaded portion 33, and the extension 34 is journaled in one of the bearings 29, as shown in Figure 1. A plug 35 having an opening therethrough, is threaded in the adjacent head 25, and an oil cup 36 is adapted to supply lubricant to the adjacent bearing. The opposite end of the shaft is provided with a relatively long extension 37 which extends through the adjacent head 25 for connection with a suitable power source. The last named head 25 may be provided with suitable packing 38 maintained in position by a gland 39 and a lubricant cup 40 is adapted to supply oil or grease to the shaft. A bearing bracket 41 is secured to the adjacent head 25 and has an upwardly extending portion 42 provided with suitable ball bearings 43. These bearings are provided to minimize lateral pull on the packing gland and adjacent bearing 30 when the device is in operation and the shaft 37 is belt driven.

Referring to Figures 1 and 6, the numeral 25 44 designates a plurality of impeller sections adapted to be mounted on the shaft 31. Each impeller section includes a hub 45 and a pair of spiral blades 48 similar in construction to the spiral ribs of an ordinary auger. It will be apparent that the blades of each impeller section are oppositely arranged at each point throughout their length. In the form of the invention described the length of each threaded section 33 of the shaft 32 is sufficient to accommodate two of the impeller sections 44, the hubs of these sections being threaded in place. Obviously two of the sections are mounted on each threaded portion 33, and the inner ends of the inner impeller sections seat against the shoulders formed at the ends of the central shaft portion 32. Outward movement of the impeller section is prevented by the inner ends of the head extension 29. It will be apparent that the blades of the impeller sections arranged on the two shaft portions 33 are oppositely pitched.

The casing and most of the other elements illustrated in Figure 4 of the drawings are identical with the corresponding elements previously described and need not be referred to in detail. In this form of the invention it will be noted that the sleeves 28 and casing extensions 24 have been eliminated and the heads 25 are secured directly against the ends of the casing, it merely being necessary to employ shorter bolts 26. In the modified form of the invention, the shaft 31 is provided with a relatively short threaded section 49 in place of the threaded portion 33, the threaded portion 49 being equal in length to one of the impeller sections 44. In this form of the invention, therefore, it will be apparent that only one of the impellers is employed on each end of the shaft 31.

If it is desired to use only one side of the pump, one of the extensions 28 may be seated in the recess 27 and may contact at its outer end with the adjacent head 25, as illustrated in dotted lines in Figure 4.

The operation of the device is as follows:

It has been found that the pump construction illustrated in Figure 4 is very efficient in operation and only a slight degree of centrifugal force is generated owing to the use of the type of impeller employed. The pump is operated by driving the shaft 37 from any suitable source of power. Water or other liquid is drawn into the casing extension 17 through the inlet pipe 28 and flows into the cylinder 16 through the passages 27 and the spaces provided between the heads 25 and the ends of the cylinder 16. As previously stated, the impeller sections on opposite ends of the shaft are oppositely pitched, and it will be apparent therefore that rotation of the shaft is adapted to pump water toward the center of the cylinder 16, and thence outwardly through the opening 12 and outlet pipe 13.

If it is found that an additional pumping head is necessary or desirable, the capacity of the pump readily may be increased without discarding anything but the pump shaft. The heads 25 in the form of the invention illustrated in Figure 4, may be removed and the shaft withdrawn, whereupon the shaft 31 illustrated in Figure 5 may be substituted. This shaft is adapted to accommodate two of the impeller sections as previously stated. One of the extensions 28 is then arranged in each recess 27 and the heads may be replaced and one of the casing extensions 24 arranged against each end of the casing. The shaft and heads then may be replaced, when the pump is ready for operation. With a plurality of impeller sections mounted on each end of the shaft 31, it will be apparent that a greatly increased pressure head may be obtained. Obviously, the device is not limited to the use of two impeller sections, it being apparent that a longer shaft, and longer extensions 24 and 28 may be employed whereby any desired number of impeller sections may be used. When the form of the pump shown in Figure 4 is employed, and a decreased pumping action is desired, one of the heads 25 may be removed and one of the sleeves 28 placed in position as shown in dotted lines in Figure 4. As is well known, an increased pumping action where desired, usually can be obtained only by discarding a pump and replacing it with one of greater capacity. With the present invention, however, the increased pumping action readily may be obtained in the manner stated without replacing any of the parts except the shaft 31.

It is to be understood that the forms of

the invention herewith shown and described are to be taken as preferred examples of the same and that various changes in the shape, size and arrangement of parts may be resorted to without departing from the spirit of the invention or the scope of the subjoined claims.

I claim:

1. A pump comprising a casing including a cylinder having its ends spaced from the adjacent portions of the casing to provide inlet passages through which liquid is adapted to flow into the ends of the cylinder, said casing being provided with an outlet opening communicating with said cylinder centrally thereof, a shaft rotatably mounted in said casing and extending axially through said cylinder, a pumping element mounted on said shaft on each side of said outlet opening and rotatable in said cylinder, means for elongating said casing axially of said shaft to accommodate an additional pumping element adjacent each of said first named pumping elements, and means for elongating said cylinder at opposite ends to receive such additional pumping elements.

2. A pump comprising a casing including a cylinder having its ends spaced from the adjacent ends of the casing to provide passages through which fluid is adapted to flow into the ends of said cylinder, said casing being provided with an outlet opening communicating with said cylinder centrally thereof, a pair of heads mounted on opposite ends of said casing, bearings carried by said heads in axial alinement with said cylinder, a shaft journalled in said bearings and extending through said cylinder, a pair of pumping elements carried by said shaft on opposite sides of said outlet opening, extension members adapted to be arranged between said heads and the adjacent portions of said casing, and means for extending said cylinder at opposite ends to accommodate additional pumping elements adapted to be mounted on said shaft adjacent said first named pumping elements.

3. A pump comprising a casing having a horizontally elongated upper portion, a cylinder forming a part of said casing and arranged in the elongated portion thereof, said casing being provided with an outlet opening communicating with said cylinder centrally thereof and being further provided with an inlet opening, the ends of said cylinder being spaced from adjacent portions of said casing whereby the ends of the cylinder are adapted to communicate with said inlet opening, spaced bearings carried by said casing in axial alinement with said cylinder and spaced from the ends thereof, a shaft journalled in said bearings and extending through said cylinder, pumping elements carried by said shaft on opposite sides of said outlet opening, and means for

spacing said bearings a greater distance apart to accommodate additional pumping elements on said shaft adjacent and outwardly of said first named pumping elements.

4. A pump comprising a casing having a horizontally elongated upper portion, a cylinder forming a part of said casing and arranged in the elongated portion thereof, said casing being provided with an outlet opening communicating with said cylinder centrally thereof and being further provided beneath said cylinder with an inlet opening, the ends of said cylinder being spaced from adjacent portions of said casing whereby the ends of the cylinder are adapted to communicate with said inlet opening, heads carried by said casing outwardly of the ends of said cylinder, bearings carried by said heads axially of said cylinder, a shaft journalled in said bearings and extending through said cylinder, pumping elements mounted on said shaft on opposite sides of said outlet opening, and extension members adapted to be mounted between said heads and the adjacent portions of said casing to accommodate additional pumping elements on said shaft adjacent said first named pumping elements.

5. A pump comprising a casing having a horizontally elongated upper portion, a cylinder forming a part of said casing and arranged in the elongated portion thereof, said casing being provided with an outlet opening communicating with said cylinder centrally thereof and being further provided with an inlet opening, the ends of said cylinder being spaced from adjacent portions of said casing whereby the ends of the cylinder are adapted to communicate with said inlet opening, heads carried by said casing outwardly of said cylinder, bearings carried by said heads in axial alinement with said cylinder, a shaft journalled in said bearings and extending through said cylinder, spiral pumping elements carried by said shaft on opposite sides of said outlet opening and rotatable in said cylinder, casing extension members adapted to be arranged between said heads and said casing, and sleeves adapted to be arranged at opposite ends of said cylinder to form continuations thereof.

6. A pump comprising a casing having a horizontally elongated upper portion, a cylinder forming a part of said casing and arranged in the elongated portion thereof, said casing being provided with an outlet opening communicating with said cylinder centrally thereof and being further provided with an inlet opening, the ends of said cylinder being spaced from the adjacent portions of said casing whereby the ends of the cylinder are adapted to communicate with said inlet opening, heads carried by said casing outwardly of said cylinder, bearings carried by said heads in axial alinement with said cylinder, a shaft adapted to

be journaled in said bearings and to extend through said cylinder, spiral pumping elements adapted to be mounted on said shaft on opposite sides of said outlet opening and 5 rotatable in said cylinder, casing extension members adapted to be arranged between said heads and said casing, each of said members having its ends corresponding in shape to one of said heads and the adjacent 10 portion of said casing, said casing being

provided with an annular recess arranged concentric with said cylinder at each end thereof, and a sleeve adapted to be inserted in each of said recesses to form a continuation of said cylinder, the outer end of each 15 of said sleeves being adapted to contact with one of said casing extension members.

In testimony whereof I affix my signature.

RHEUBEN M. CLARK.
